HYDRAULIC BRAKE, ESPECIALLY FOR
LIFTING TRUCKS

Jakob Loef, Moosburg, Germany

Application September 3, 1931, Serial No. 561,033
Renewed April 4, 1935

6 Claims. (Cl. 188—96)

The object of the present application is a hydraulic brake, as is frequently employed, recently more especially in lifting trucks. In the application of brakes of this kind it has been found that they do not give full satisfaction. The hydraulic brakes in lifting trucks are supposed to transform the potential energy of the lifted load into working power and heat when they are lowered. As is generally known, brakes of this kind consist of a cylinder and a piston gliding in it. The piston contains a boring which lets the oil pass through freely in lifting, whereas in lowering only a limited cross-sectional area is given free so that the movement of the piston can be executed very slowly, thus retarding in an equal manner the lowering of the load and to the same degree in which the pressure of the compressed fluid is able to press the oil back through the free opening. The reflux-velocity of the oil is proportional to the pressure produced in the oil-brake, and this pressure again depends upon the load resting on the lifting-frame or the platform. This results in the disadvantage that big loads are lowered quickly and light loads considerably more slowly, giving rise in loads between 0 and 1500 kilos to differences of time which are 15 to 30 times as big.

It need hardly be emphasized that this fault is felt to disadvantage in practical work. Particularly the lowering of the empty truck or the unloaded platform takes much too long, whereas in the case of big loads the repressing effect of the brake is at times insufficient.

Several solutions have become known which are supposed to remedy this fault. It is particularly well known to build in a valve standing under the action of a spring which for quite light loads, i. e. for an empty truck plus the weight of a platform, holds open a larger reflux-cross-sectional area and which brings the contraction calculated for the maximum load into use only with a load which exceeds the one before-mentioned.

But even this solution did not give satisfaction in practical work, for it merely provided a shortening of the lowering time for the unloaded truck, while light loads from about 100 to 150 kilos still required far too much time.

It has been attempted to remedy this fault by a device which has become known under the term of "lowering regulator" and which consists in an adjustment by hand of the valve, so that a flowing-through section of different size is given free for the reflux of the oil.

The objection to this solution is that it does

not work automatically and that it requires the control of a workman attending to it. On the other hand it also holds certain dangers as the oil-brake adjusted for moderate loads may, with heavier loads, cause a jerky lowering and thereby damage the load and the frames and endanger the workman.

The constructions above described are considerably improved by the arrangement described in the following. Their faults are avoided and the advantage hitherto unknown is obtained that the oil-brake automatically adjusts itself to the load and that the lowering-velocity can be maintained practically equal for all loads.

The object of the present application is illustrated by way of example in the accompanying drawings in which—

Fig. 1 represents a longitudinal section through the oil-brake,

Fig. 2 the construction of a piston,

Fig. 3 the piston-pin,

Fig. 4 a top-view of the piston-pin of Fig. 3,
Figs. 5 and 6 different constructions of the piston.

Figs. 7, 8 and 9 different constructions of the pin,

Figs. 10 and 11 other constructions of the piston,

Fig. 12 the lifting truck with the brake in top view,

Fig. 13 the lifting truck of Fig. 12 in lateral view with lowered platform and

Fig. 14 with raised platform.

The oil-brake consists, in the manner known, of a brake-cylinder 1, in which the piston 2 slides. This piston 2 is held true by means of piston-rings. The brake-cylinder 1 is closed at its front end by the cover 4 and at its rear end by the cover 5. The piston-rod 6, around which a screw-spring 7 is laid, passes through the rear cover 5, the screw-spring 7 acting on the piston 2 and supporting itself against the cover 5. The piston-rod 6 is constructed hollow and contains in its inside another screw-spring 8 which presses with one end against the head 9 of the pin 10 which is passed through the piston. In the piston 2 there is a bore 11 which can be closed or opened by the pin 10. The oil can flow through this bore from the front to the back of the piston, thus effecting a locking of the piston. The pump is fastened with its front part 12 to the driving-frame and with the eye 13 of the piston-rod 6 to the lifting-frame. The piston 2 is thereby pulled into the rear position and the major part of the oil is in front of the piston. The pis-

ton-rod 6 is built in the form of a tube in its front part 14 the latter being provided with openings 15 from which the oil can emerge from the piston. With the exception of a valve consisting of a pin 9 and 10 the brake above described is known. Therefore the valve and the kind of gear is new.

It would be possible to obtain the intended effect by shifting the piston on the piston-rod itself. 10 This solution is, however, practically not feasible in the case of lifting-trucks for the reason that the pressure resting on the piston becomes so high in ordinary loads that it is not possible to fit a spring in the brake which could stand this 15 pressure. Therefore—and that is the guiding thought of the present application—the cross-sectional area of the pin 10 is so calculated that a spring 8 resting on this pin can be constructed strong enough to guide the pin against the pressure and be housed in the piston-rod 14 which for this purpose is made hollow. For constructive reasons the piston-rod is not hollowed out in its entire length but is divided in a hollow part 14 and a solid part 6. The hollow part still possesses a slight enlargement 16 in which a piston 9 fastened to the pin-valve 10 slides. This enlargement serves to stop the stroke for the valve 10. The piston itself possesses a bore 11 which is carried through to about its middle and which 30 ends in a circumferential groove 17 cut into the bore in which the pin valve 10 slides, as shown in Fig. 2. The bore 11 can also be carried out obliquely (Fig. 2). It is also possible to connect the groove 17 to a bore 17a terminating in a bore 18 as shown in Fig. 5 so that the brake-fluid need not take its way through the central bore of the piston and does not enter the inside of the piston-rod but leaves the piston through the bore 18. In order to effect the entry of the fluid from 40 the central bore into the inside of the piston-rod 14, the piston 9 of the valve 10 has been provided with a bore as shown in Figs. 3 and 4, while the piston-rod 14 possesses bores 15 through which the oil can emerge from the piston rod into the 45 cylinder 1. The valve 10 can slide in longitudinal direction in the bore 16 of the piston-rod, and corresponding to this longitudinal mobility the pin may be of various constructions which serve to contract the cross-section. These constructions may consist of a conically tapering groove 19 of the pin as shown in Fig. 3. They may consist also of a conical turning 20 (Fig. 5) or of an arrangement of furrows 21 (Fig. 7) or a number of holes with increasing diameter 22 (Fig. 8) 55 or finally of holes with invariable diameter but with increasing density, 23 (Fig. 9). The essential point is that the cross-section narrows under the pressure of the enclosed fluid, by the pin 10 being pushed into the piston through the pressure 60 lying on its head-end, against the action of the spring 8. Alternatively as illustrated in Fig. 6 it is possible to perforate the pin at 10a, which would offer constructive advantages in so far as its diameter becomes enlarged, since the ring-65 surface gives the same cross-section as the face of the solid pin only with enlarged diameter. In this case the means to contract the cross-sectional area are arranged inside the piston and the bores do not serve for the admission but for the exhaust 70 of the brake-fluid.

The manner of action of the oil-brake is as follows:

When the lifting-truck is raised the piston is drawn from the cylinder, the spring 7 which is 75 fitted on the outside of the piston-rod 6, 14 being

compressed. The brake-fluid takes its way through the holes 15, the hollow interior of the piston-rod 14, the bore 19 of the valve 10, the bevelment of the pin 10, the channel 11 and collects behind the piston. During this process 5 the valve is in the position on the far left, as shown in the drawings, and the widest cross-section of the pin is opposite the groove 17.

When the lowering movement is started the load presses on the piston by means of the piston-rod and thereby on the fluid compressed in the cylinder in front of the piston. Proportionately to this pressure the pin of the valve is pushed backward in the piston 2, the cross-sectional area becoming narrower and the reflux-velocity of the 15 brake-fluid correspondingly slower.

As indicated in Figure 10 of the drawings, the piston rod may be made rigid with the piston and in this particular construction the valve pin 10 extends in an offset position through the piston 2 20 and is connected to a spring actuated lever 25.

As will appear from Fig. 11, instead of one pin several may be used working either separately or 25 jointly by means of a disk 26 uniting the pins and acted upon by a spring 27.

Figs. 12, 13 and 14 show a lifting-truck of this kind with the brake. The lifting-truck consists of the driving-frame or carrying-frame or carrying-frame proper 24, in which fixed wheels 25 are supported at the rear end, whereas the guiding wheels 28 which can be swung round are provided at the cross-piece 27 on the forward part. Above the carrying-frame is the lifting-frame 29 which can be swung on the axle 31 of the hind wheels by means of guide-rods 30 and around 30 the forward pivot 32 by means of guide-rods not shown, and is thereby lifted to a maximum height. This lifting movement is effected by means of the radius-bar 33 which engages a lifting-jaw 35 on the lifting-frame by means of a head 34. 40 A transom-bar 36 is provided at the carrying frame 24 to which the rear end of the brake 1 is fastened. The piston 6 which can be pulled out of the brake is fastened with its front part 13 to the transom-bar 37 which again is arranged at 45 the upper frame 29. When the lifting-truck is raised through the radius-bar 33 catching behind the jaw 35 with its head 34, the brake is pulled out, the spring 7 being compressed. Now, in lowering, the upper frame will only gradually be able 50 to go down according to the flow of oil through the piston. The velocity of lowering respectively of the oil-passage depends proportionally on the load, so that with heavy loads the frame drops slowly and with light loads the upper frame drops 55 quickly.

Having now particularly described and ascertained the nature of my said invention and in what manner the same is to be performed I declare that what I claim is:

1. In a lifting truck having a carrying frame and a lifting frame movable upon said carrying frame, a hydraulic brake for checking the lowering movement of the lifting frame, comprising a fluid cylinder having one end connected to one of said frames, a piston rod received in said cylinder through the free end thereof and connected at its outer end portion to the other of said frames, a piston carried by the piston rod and reciprocating with the latter in the cylinder, a passageway formed in said piston and establishing communication between the cylinder spaces in front and in back of the piston, a valve 65 slidably mounted in said piston and interposed in the passageway, means on said valve to vary 70 the communication between the cylinder spaces in front and in back of the piston, a valve 75 spaces in front and in back of the piston, a valve slidably mounted in said piston and interposed in the passageway, means on said valve to vary the communication between the cylinder spaces in front and in back of the piston, a valve

the cross sectional area of said passageway with the sliding movement of the valve, spring means acting upon the valve and normally urging the latter to a position corresponding to the maximum effective cross sectional area of said passageway, and other spring means encompassing said first-named spring means and acting upon the piston.

2. In a lifting truck having a carrying frame and a lifting frame movable upon said carrying frame, a hydraulic brake for checking the lowering movement of the lifting frame, comprising a fluid cylinder having one end connected to one of said frames, a piston rod received in said cylinder through the free end thereof and connected at its outer end portion to the other of said frames, the inner end portion of said piston rod having a hollowed section, a piston carried by said section of the piston rod and reciprocating with the latter in the cylinder, a passageway formed in said piston and establishing communication between the cylinder spaces in front and in back of the piston, a pin valve slidably mounted in said piston and interposed in the passageway, means on said pin valve to vary the cross sectional area of said passageway with the sliding movement of the valve, a head rigid with said valve and positioned within the hollowed section of the piston rod, a coil spring disposed 25 within the hollowed section of the piston rod and bearing upon the head of the valve, and another coil spring about the piston rod and acting upon the piston.

3. In a lifting truck having a carrying frame and a lifting frame movable upon said carrying frame, a hydraulic brake for checking the lowering movement of the lifting frame, comprising a fluid cylinder having one end connected to the carrying frame, a piston rod received in said cylinder through the free end thereof and connected at its other end to the lifting frame, the inner end portion of said piston rod having a hollowed section, a piston carried by said section of the piston rod and reciprocating with the latter in the cylinder, a passageway formed in said piston and establishing communication between the cylinder spaces in front and in back of the piston, a pin valve slidably mounted in said piston and interposed in the passageway, said pin valve having a portion extending into the hollowed section of the piston rod, means on said pin valve to vary the cross sectional area of said passageway with the sliding movement of the valve, spring means disposed within the hollowed section of the piston rod and acting upon the extended portion of the pin valve, and other spring means acting upon the piston.

4. A hydraulic brake of the type used for checking the lowering movement of a lifting truck platform and comprising a cylinder, a piston fitted for sliding movement in said cylinder, with the movement of said piston in said cylinder resisted by a fluid, said piston having a bore, a

valve mounted in said bore, said valve being movable in said bore in response to the pressure generated through movement of the piston against the fluid in said cylinder, a spring for resisting said pressure induced movement of the valve, said piston having a passage leading from the pressure side of said piston to said valve bore, said valve being normally maintained by its spring in a position in which it permits substantially free flow of liquid through said passage and said valve bore to the other side of the piston, and means whereby the fluid pressure may be directed against the said valve independently of said passage to urge said valve into positions corresponding to varying restriction of the flow of liquid through said passage.

5. A hydraulic brake of the type used for checking the lowering movement of a lifting truck platform and comprising a cylinder, a piston fitted for sliding movement in said cylinder, with the movement of said piston in said cylinder resisted by a fluid, said piston having a bore axially formed therein parallel to the direction of movement of said piston and in communication with the pressure end of said piston, a valve mounted in said bore for movement parallel to the movement of said piston and exposed to the pressure generated at the pressure end of said piston, said valve being movable in said bore relatively to said piston in response to the pressure generated through movement of the piston against the fluid in the cylinder and in a direction reverse to the direction of movement of said piston, a spring for resisting the said pressure induced movement of the valve relatively to the piston, said piston having a passage leading from the pressure side of said piston to said valve bore and then to the other side of said piston, said valve being normally maintained by its spring in a position in which it permits substantially free flow of liquid through said passage to the other side of the piston, the movement of said valve relatively to said piston being effective to restrain the flow of liquid through said passage.

6. A hydraulic brake for checking the lowering movement of a lifting truck comprising a cylinder, a piston fitted for sliding movement in said cylinder, said piston having a valve bore terminating on the pressure side of the piston, a graduated valve in said bore and having a portion thereof disposed in said bore so as to be actuated by the pressure on the pressure side of the piston, said piston having a further passage leading to said valve bore from the pressure side of said piston, a spring adapted to urge said valve into a position in which it permits substantially free flow of liquid through said passage and said valve, the pressure in said piston valve bore against the said valve portion being effective to move said valve against the spring pressure and into a position substantially restricting the flow of liquid through said passage.

JAKOB LOEFF.
